CLAMPING APPARATUS

Application filed January 2, 1931. Serial No. 506,124.

This invention relates to an apparatus which employs a device in the nature of a press and devices in the nature of clamps, and which is especially useful for the purpose of securing lengths of wood together, which may later be cut into wooden tiles for use in floors, panels, or other woodwork.

The object of the invention is the provision of an apparatus wherein a plurality of long lengths of wood may be glued together with uniform pressure distributed throughout the length of the lengths of wood, and in which a composite length of wood may be held in tightly compressed position after being removed from the pressure-applying device to permit use of the device for succeeding lengths of wood which are glued together.

In the accompanying drawing:

Fig. 1 is a side elevation of the device constructed in accordance with the invention.

Fig. 2 is a section taken on line 2-2 of Fig. 1.

Fig. 3 is a detail view of the clamping members.

Fig. 4 is a section taken on line 4-4 of Fig. 3.

In a copending application I have described a method for the making of wooden end grain tile useful for floors, and in this method a number of lengths of wood are glued together to form a composite length of wood, and then this composite length of wood is sliced up into end grain tile. Such a composite length of wood is shown at 1 in the accompanying drawing, and as viewed in Fig. 2, is composed of four lengths of wood 2, each similar in cross section, and a central length of wood 3.

These several lengths of wood are glued together to form an end design, as illustrated in Fig. 2, and from the composite length of wood the tiles are severed. The apparatus for gluing these long strips of wood together consists of a base 5 which may be suitably supported upon a table or the like (not shown) or which in itself may be provided with supporting legs. This table is provided with a plurality of blocks 6, each being recessed for receiving a clamp, as will later be more clearly described. The device may

include end uprights 7 which support a shaft 8 journaled at 9 and having an end wheel 10 with operating handle 11.

At spaced points along the shaft the same is provided with a gear 12 each for engagement with a rack-like plunger 13. A longitudinally extending support or brace 15 may be provided which has openings 16 for guiding the plungers 13 and which may also support journals 17 for the shaft. As illustrated in Fig. 2 the lower end of each rack-like plunger is bifurcated much in the form of an inverted Y as shown at 18.

A clamping device is shown in Fig. 2, and which consists of two halves 20 and 21, and which consists of two halves 20 and 21, and the arms of one half are bifurcated, whereas the arms of the other half are reduced in thickness near their ends so that they may interfit, as shown in Fig. 4. In this figure the half 20 has arms with reduced ends 22, whereas the half 21 has arms with bifurcated portions 23. The two bifurcated parts are apertured as at 24 and the part 22 is bifurcated as at 25, and these apertures are adapted to align to receive a wedge 26. Preferably the apertures in the arms are positioned at a 45° angle to the arms.

Where the composite block, the members of which are glued together, is to be square in cross section, these clamps may form a square, as shown, although an oblong or other shape may be used. In securing together a number of wooden lengths for a composite length of wood, the sections 21 of the several clamps are placed in the recessed blocks 6 with the sections 20 detached therefrom. The several pieces of wood may now be built up, being supported by the arms of the clamp part 21 with a suitable glue having been disposed between the abutting faces of the lengths of wood. Whereupon the upper sections 20 of the clamps may be placed over the composite length of wood thus built up with the ends of the arms clamping devices interfitting as shown in Fig. 2.

The plungers are now actuated to bring the inverted Y-shaped members 18 down into contact with the clamps by means of rotating the hand wheel 10. The plungers are brought down with sufficient force to tightly

compress the parts of the composite length of wood together. Suitable power means can be provided, if necessary, in place of the hand wheel 10.

4. This having been done a wedge 26 is driven into the aligning apertures in each clamp device, as shown in Fig. 2. These apertures are sufficiently disaligned so that the wedges draw the two clamping parts together. This 10 tightly clamps the several wooden pieces together so that the plungers may be now raised. The composite length of wood with the clamps applied thereto may be lifted from the press device and laid aside until 15 the glue is sufficiently dry. This permits use of the press again in repeated operations without involving the necessity of keeping the press inoperative while the glue is drying. It will be understood that with one of such 20 press devices there may be used a multiplicity of clamps.

I claim:

1. An apparatus for the purpose described, comprising in combination a press having 25 a plurality of plungers, a V-shaped supporting member positioned below each plunger, a V-shaped part of a clamp adapted to be supported by each supporting member, said supporting members being recessed for receiving and holding said clamp parts, said clamping parts being adapted to receive a plurality of articles to be attached together, complementary clamping parts of inverted V-shape adapted to fit over the articles, means 30 for actuating the plungers to engage the complementary clamp parts to urge the clamp parts together and compress said articles, means for securing the clamp parts together to hold the articles thus compressed whereby 35 to permit of removal from the press of the articles together with the clamps.

2. An apparatus for the purpose described, comprising in combination a press having 40 a plurality of plungers, a V-shaped supporting member positioned below each plunger, a V-shaped part of a clamp adapted to be supported by each supporting member, said clamp parts being adapted to receive a plurality of articles to be attached together, complementary clamp parts of inverted V-shape adapted to fit over the articles, means 45 for actuating the plungers to engage the complementary clamp parts to urge the clamp parts together and compress said articles, means for securing the clamp parts together to hold the articles thus compressed whereby 50 to permit of removal of the articles together with the clamps from the press.

3. An apparatus for the purpose described, comprising in combination a press having a plurality of plungers, a V-shaped supporting member positioned below each plunger, a V-shaped part of a clamp adapted to be supported by each supporting member, said 55 clamp parts being adapted to receive a plu-

rality of articles to be attached together, complementary clamp parts of inverted V-shape adapted to fit over the articles, means for actuating the plungers to engage the complementary clamp parts to urge the clamp parts together and compress said articles, means for securing the clamp parts together to hold the articles thus compressed whereby to permit of removal of the articles together with the clamps from the press, said plungers having an inverted Y-shaped member for engaging with the corner of the said complementary parts of the clamps. 70

4. A clamping device comprising a member of angle construction having a pair of angularly disposed arms, a similarly shaped complementary member, said members being adapted to cooperate to form an area between them for the reception of articles to be clamped and with their arms overlapping, each of said arms being apertured, and a wedge adapted to be driven through the apertures of the overlapped arms to urge the complementary members together in clamping relation. 80

5. A clamping device comprising a member of angle construction having a pair of angularly disposed arms, a similarly shaped complementary member, said members being adapted to cooperate to form an area between them for the reception of articles to be clamped and with their arms overlapping, each of said arms being apertured, and a wedge adapted to be driven through the apertures of the overlapped arms to urge the complementary members together in clamping relation, said apertures being relatively elongated and being disposed at an angle substantially 45° from the direction of extension of its respective arm. 90

6. A clamping device comprising a member of angle construction having a pair of angularly disposed arms, a similarly shaped complementary member, said members being adapted to cooperate to form an area between them for the reception of articles to be clamped and with their arms overlapping, some of said arms being bifurcated and others being reduced in cross section, the reduced portion fitting between the bifurcated parts, the arms having apertures through the bifurcated parts and reduced portion, and a wedge adapted to be driven in the apertures, said apertures being normally partially disaligned whereby the wedge draws the two complementary members together in clamping relation. 100

In testimony whereof I affix my signature.

SAMUEL D. BUTTERWORTH.
